Primary Examiner—Louis S. Zarfas**Assistant Examiner—Eric Watterson****Attorney, Agent, or Firm—Harold H. Dutton, Jr.; Diane F. Liebman****[57] CLAIM**

The ornamental design for a toilet seat lifter, as shown and described.

DESCRIPTION

FIG. 1 is perspective view of a toilet seat lifter showing my new design with the foot lever of the petal portion in the up position;

FIG. 2 is a top view of the seat-engaging portion thereof;

FIG. 3 is a bottom view thereof;

FIG. 4 is a front view thereof;

FIG. 5 is a rear view thereof;

FIG. 6 is a right side view thereof;

FIG. 7 is a left side view thereof;

FIG. 8 is a top view of the pedal portion thereof, with the foot lever shown in the down position;

FIG. 9 is a bottom view thereof;

FIG. 10 is a left side view thereof; The right side is a mirror image of the left side;

FIG. 11 is a front view thereof; and,

FIG. 12 is a rear view thereof.

The broken lines showing the toilet seat are for illustrative purposes only and form no part of the claimed design.
